INFINITY SCARF WITH SECURE POCKET

FIELD OF THE INVENTION

The present invention relates to ladies clothing and, more particularly but without limitation, to neck scarves.

BRIEF DESCRIPTION OF THE DRAWINGS

The accompanying drawings, which are incorporated into and form a part of the specification, illustrate one or more embodiments of the present invention and, together with this description, serve to explain the principles of the invention. The drawings merely illustrate a preferred embodiment of the invention and are not to be construed as limiting the scope of the invention.

FIG. 1 is a diagrammatic illustration of a rectangular panel of fabric that can be formed into a cylinder in accordance with a preferred embodiment of the present invention.

FIG. 2 is a diagrammatic illustration of a neck scarf formed from the rectangular panel of fabric shown in Figure A.

FIG. 3 is a front view of a neck scarf made in accordance with a preferred embodiment of the present invention.

FIG. 4 is a front perspective view of the scarf shown in FIG. 3 with the forward part of the cylinder allowed to hang down exposing the inner surface of fabric panel with the zippered pouch.

FIG. 5 is an enlarged view of the open pouch showing illustrative dividers sized to fit different sized articles.

FIG. 6 shows a cell phone partially inserted into the open pocket on the outside of the pouch.

FIGS. 7A-7E illustrate sequentially the steps for enclosing the pouch inside the scarf.

FIGS. 8A-8F illustrate various ways to configure the scarf for different purposes.

DETAILED DESCRIPTION OF THE PREFERRED EMBODIMENT(S)

Travelers are well aware of the need to have certain items, such as passports and cellphones, securely stowed but still easily accessed when needed. From shoulder bags to "fanny packs," numerous products are available for this purpose. The present invention provides a style neck scarf for carrying personal items. The scarf, which preferably is in the form of an infinity scarf, is an elongate rectangular panel of fabric with the ends joined to form a fabric cylinder. This scarf provides a way to secure personal items that is safe, comfortable, multi-functional, gender-neutral, and fashion forward.

Turning now to the drawings in general and to FIGS. 1 and 2 in particular, there is shown therein a neck scarf, designated generally by the reference number 10. The scarf 10 comprises a rectangular panel "P" of fabric illustrated in Figure A. The panel P (FIG. 1) has first and second ends 12 and 14 and the upper and lower edges 16 and 18. While the dimensions of the panel P may vary, in some embodiments the length L of the panel may be about twice the transverse dimension or width "W" of the panel. (See FIG. 1.) By way of example only, the length L may be about 45-50 inches, and the width W may be about 24-28 inches.

As seen in FIG. 2, when the end edges 12 and 14 are joined at the seam S, the panel P forms a fabric cylinder C having a sidewall 20 with an inner surface 24 and an outer surface 26. The upper edge 16 forms an open upper end 30,

and the lower edge 18 forms an open lower end 32. In the preferred embodiment, the cylinder C has the shape of a right circular cylinder, that is, a cylinder that has a closed circular surface having two parallel bases on both the ends and whose elements are perpendicular to its base.

The construction of the scarf 10 may vary. The finished scarf 10 may be a single layer of fabric or a double layer. Virtually any flexible fabric or other material, textile or non-textile, woven or non-woven, may be used to make the scarf 10. In some embodiments, the scarf 10 is made of a lightweight, elastic jersey knit.

The present embodiment of the scarf 10 is a single layer, wherein each of the upper and lower edges 12 and 14 are finished with a hem 36 and 38, respectively (Fig. A). A first elastic section 40 may be provided on the upper edge 16, and a second elastic section 42 may be provided on the lower edge 18. This can be accomplished by any suitable method. For example, a strip of elastic (not shown) may be stitched onto the inner surface 24 of the fabric panel P near the edges 16 and 18 prior to hemming.

In the example shown, the elastic sections 40 and 42 are roughly centered along the length L of the edges 16 and 18, respectively, and are about 6 inches long in the resting or non-extended state. As illustrated in FIGS. 1 and 2, each of the elastic sections 40 and 42 extend only partially around the circumference of the upper and lower edges, respectively. Ideally, the elastic sections 40 and 42 are of about equal length and generally spaced a distance apart and directly across from each other. However, the length and relative positions of the elastic sections 40 and 42 may vary.

With continuing reference to FIGS. 1 and 2, a closable pouch 50 may be provided on the inside surface 24. While the position of the pouch 50 on the panel P may vary, it is advantageous for a reason that will become apparent to 35 position the pouch generally between the elastic edge sections 40 and 42. In the illustrative embodiment, the closure is a zipper 52. Of course, the closure means, when included, may vary. For example, buttons, snaps, ties, hooks, or hook-and-loop fasteners could be used instead. One or more 40 variably sized compartments 54a and 54b (FIG. 5) may be formed on the inside of the pouch 50 for holding articles, such as credit cards, cell phones, pens/pencils, and so forth.

As seen in FIGS. 1 and 3, the scarf 10 may be provided with one or more snaps or other connectors, such as the first 45 and second pairs of snaps 58a and 58b and 60a and 6b. Preferably, the snaps 58a and 58b and 60a and 6b are positioned on the inside edges 16 and 18 on each end of the each of the elastic sections 40 and 42. Once items are placed in the pouch 50 and/or pocket 62, and the zipper 52 (or other closure device, if any) is closed, the elastic sections 40 and 42 can be brought together in close proximity and then the snaps 58a and 58b and 60a and 6b engaged. Specifically, the snaps 58a and 58b are connected to each other, and the snaps 60a and 6b connected to each other. This lessens the likelihood that scarf 10 will fall out of the desired position enclosing the pouch 50 and pocket 62, as described hereafter.

An open pocket 62 (FIG. 1) may be included on the outside of the pouch 50. This allows the user to quickly access articles in the pocket 62 without having to open the 60 zipper 54 to access the pouch 50. For example, as seen in FIG. 6, depending on the situation, a user may prefer to stow her cell phone 58 in the open pocket 62, while credit cards and a passport may be more securely enclosed in the zippered pouch 50.

Although not depicted in the drawings, the pouch 50 or the pocket 62, or both, may be lined or covered with or otherwise protected by an RFID blocking material. As the

composition and use of these materials is generally known, they are not described in detail. The use of these protective materials will protect the articles, such as credit cards, inside the pouch or pocket or both from being scanned, accessed, or otherwise acted on surreptitiously.

Turning now to FIGS. 7A-7E, one use of the scarf will be explained. In the exemplary configuration shown in FIG. 7A, the scarf 10 is worn over one shoulder and under the opposite arm. In this configuration, the pouch 50 hangs comfortably against the wearer's waist or midriff area. With items (not shown) secured inside the pouch 50 and/or pocket 60, the lower elastic edge section 42 is pulled up and over the upper elastic section 40 (FIG. 7B). Then, as illustrated sequentially in FIGS. 7C-7E, pulled down, over, and back up under around the pouch 50. Now it will be appreciated that the elastic sections 40 and 42 pull or hug the enclosed pouch 50 snugly. Thus, the contents of the pouch 50 are held close to the body and doubly wrapped in the fabric of the scarf 10. This makes the contents of the pouch 50 physically inaccessible even to an expert pickpocket. Additionally, with the RFID blocking material, the contents are inaccessible electronically.

Notably, although the scarf 10 is shown in the drawings worn over the user's clothing, alternately it could be worn underneath clothing. Still further, when not in use, the scarf 10 can be folded or rolled into a compact stowage position that will fit easily into a coat pocket or handbag or other carrying case. Additionally, the rolled up scarf 10 can also serve as a neck pillow.

Several other uses of the inventive scarf 10 are illustrated in FIG. 8A-8F. Worn around the shoulders, as seen in FIG. 8A, the scarf serves as shawl or warming wrap. When not in use to hold valuables, the scarf 10 can be worn in a fashionable double-wrap style, as depicted in FIG. 8B. Draped over the head and around the arms, the scarf serves as a privacy scarf when using a phone or tablet device or reading printed matter, as illustrated in FIG. 8C. This is particularly advantageous when using electronic devices, as the scarf reduces the light affecting the screen. Even with printed matter, the scarf prevents other "prying eyes" from observing the written content.

FIG. 8D shows the scarf 10 draped over the user's face, serving as an eye mask. In FIG. 8E, a fashionable double loop head cover arrangement. Still further, as seen in FIG. 8F, the scarf 10 can be double looped around the face and neck so that sections of the scarf criss-cross across the wearer's face serving as a protective mask to prevent transmission of air borne organisms or to protect one's identity.

Referring again to FIG. 1, while the size and configuration of the pouch 50 and pocket 62 may vary, in some embodiments, the pouch 50 is secured to the inside 24 of the scarf 10 only across the top edge 64. The size of the pocket 62 may be large enough to enclose the pouch 50 when turned inside out. This would position the opening of the pocket 62 behind the pouch 50 as seen in FIG. 1, which is between the back of the pouch and the inside surface 24 of the scarf 10 behind it. This may be desirable to contain more securely objects inside the pocket 62, such as a cell phone for example.

Now it will be apparent that the scarf 10 of the present invention may be worn in several styles, some for purely ornamental purposes, and some for functional purposes, such as sleeping or reading. The views shown in the drawings are illustrative and not limiting.

The embodiments shown and described above are exemplary. Many details are often found in the art and, therefore,

many such details are neither shown nor described herein. It is not claimed that all of the details, parts, elements, or steps described and shown were invented herein. Even though numerous characteristics and advantages of the present inventions have been described in the drawings and accompanying text, the description is illustrative only. Changes may be made in the details, especially in matters of shape, size, and arrangement of the parts within the principles of the inventions to the full extent indicated by the broad meaning of the terms of the attached claims. The description and drawings of the specific embodiments herein do not point out what an infringement of this patent would be, but rather provide an example of how to use and make the invention. Likewise, the abstract is neither intended to define the invention, which is measured by the claims, nor is it intended to be limiting as to the scope of the invention in any way. Rather, the limits of the invention and the bounds of the patent protection are measured by and defined in the following claims.

What is claimed is:

1. A scarf comprising:
a fabric cylinder having a sidewall with an inner surface and an outer surface, an open upper end having an upper edge, and an open lower end having a lower edge, wherein the cylinder has a circumference; wherein the upper edge comprises an upper edge elastic section extending only partially around the upper edge; wherein the lower edge comprises a lower edge elastic section spaced apart from and opposite the upper edge elastic section and extending only partially around the lower edge;

a pouch on the inner surface of the sidewall between the upper edge elastic section and the lower edge elastic section and wherein the pouch has a closure.

2. The scarf of claim 1 wherein the upper edge elastic section is about the same length as the lower edge elastic section.

3. The scarf of claim 1 further comprising an open pocket superimposed over the pouch.

4. The scarf of claim 1 wherein the fabric cylinder is a right cylinder, wherein the cylinder has a width extending between the upper and lower ends, and wherein the circumference of the cylinder is about twice the width.

5. The scarf of claim 1 wherein the pouch is lined with RFID blocking material.

6. The scarf of claim 1 wherein the pouch closure comprises one or more of the following: snaps, zipper, hooks, buttons, ties, and hook-and-loop fasteners.

7. The scarf of claim 1 further comprising connectors for securing the elastic sections adjacent to each other when the scarf is being worn.

8. The scarf of claim 7 wherein the connectors are snaps.

9. A method for securing at least one valuable, comprising:

donning the scarf of claim 1;
placing the at least one valuable in the pouch;
positioning the lower edge of the scarf over the upper edge of the scarf and tucking the lower edge under the pouch so that the pouch is double-wrapped inside the scarf.

10. The scarf of claim 1 wherein each of the upper and lower edge elastic sections comprises an elastic strip attached to the upper and lower edge, respectively, to form an upper edge expandable gathered section and a lower edge expandable gathered section.
